EXPANSIBLE BRACELET OR THE LIKE

Samuel Meyerson, Brooklyn, N. Y.

Application December 14, 1950, Serial No. 13,434

Term of patent 14 years

(Cl. D45—4)

To all whom it may concern:

Be it known that I, Samuel Meyerson, a citizen of the United States of America, residing in Brooklyn, county of Kings, and State of New York, have invented a new, original, and ornamental Design for an Expansible Bracelet or the like, of which the following is a specification, reference being had to the accompanying drawing, forming part thereof, in which

Fig. 1 is a top plan view of an expansible bracelet embodying the new design, a portion of the center being broken away for convenience of illustration only.

Fig. 2 is a side elevation thereof with the conventional bottom links illustrated in broken lines.

Fig. 3 is a top plan view showing the bracelet in an expanded position.

Fig. 4 is an enlarged perspective view of one of the top links.

Fig. 5 is a transverse section of one of the top links taken on the line 5—5 of Fig. 4, and

Fig. 6 is a transverse section of one of the top links taken on line 6—6 of Fig. 4.

The dominant feature of my design resides in the elements shown in full lines.

I claim:

The ornamental design for an expansible bracelet or the like, as shown and described.

SAMUEL MEYERSON.
